UNITED STATES PATENT OFFICE.

HALVOR M. OLSEN, OF CHICAGO, ILLINOIS, ASSIGNOR TO AMERICAN ELECTRIC TELEPHONE COMPANY, OF CHICAGO, ILLINOIS, A CORPORATION OF NEW JERSEY.

ANNUNCIATOR.

No. 811,083.

Specification of Letters Patent.

Patented Jan. 30, 1906.

Application filed May 16, 1901. Serial No. 60,792.

To all whom it may concern:

Be it known that I, HALVOR M. OLSEN, a citizen of the United States of America, and a resident of Chicago, Cook county, Illinois, have invented a certain new and useful Improvement in Annunciators, of which the following is a specification.

My invention relates to improvements in annunciators generally, and has special reference to those in which a long or relatively great movement or throw of the signal-indicating device is required and in which but a small movement of the armature of the operating-magnet is obtainable or desirable.

It has for its objects the provision in annunciators of the class described of simple apparatus in which but a slight movement of the armature is required to fully throw and expose the signal-indicator, of a construction permitting the use of metals of good wearing qualities where needed, and one in which but slight magnetic power is required for its operation, whereby a cheap, efficient, and durable device is obtained and one that is inexpensive to maintain and operate.

To the accomplishment of these and such other objects as may hereinafter appear the invention consists in an annunciator having a magnet secured on one side of a support with a longitudinal armature carrying an arm adapted to operate a pivoted signal indicator or target on the other side the support, the signal indicator or target consisting of a segmental portion fulcrumed at the center of its curve with a rearwardly-extending portion adapted to be acted upon by the armature through its arm. A segmental cover is supplied for the targets, having suitable apertures through which the targets are exposed.

The invention further consists in the parts and combinations hereinafter fully described, and particularly pointed out in the claims, reference being had to the accompanying drawings, forming a part of this specification, in which the same reference-figures designate like parts throughout the several views, and in which—

Figure 1 is a plan view of my improved annunciator. Fig. 2 is a side elevation of the same. Fig. 3 is a front end elevation. Fig. 4 is a perspective view of a segmental target. Fig. 5 is a perspective view of the front seg-

mental plate, and Fig. 6 is a perspective detail view of the target-operating arm. 55

In the figures, 2 and 3 are supporting plates for the magnet and target and are properly spaced apart by the blocks or thimbles 4, which are secured between the two plates by screws or in any desired manner. 60 At the rear of the plate 2 a metal block 5 is placed to better secure the end piece 6 of the electromagnet to the support, an end piece 7, similar to the end piece 6, being provided for the other end of the magnet, both of which 65 snugly fit the core 8 thereof passing centrally through the coil 9. These end pieces serve to extend the magnetic circuit to their upper edges, where the armature 10 is located, and tends to close the same when the 70 coil is energized. Insulating-blocks 11 and 12 are placed at the two ends of the magnet-coil in the usual way, the terminals 13, connected with the magnet-coil, being located in the rear block 11. The armature 10 is 75 provided with a downwardly-extending portion 14, through which an adjusting-screw 15 passes to prevent too great movement of the same. Both the horizontal and vertical 80 portions of the armature are cut away centrally to lighten the construction. It is pivoted at its rear end on the pivot-plate 14^a, having the rearwardly-extending pivot-arms 14^b, said plate being secured in any desired manner to the end piece 7 of the magnet. 85

Side strips 20 and 21 are secured to the insulating-blocks 11 and 12 and have rearwardly-extending portions 22, to which circuit-wires are adapted to be connected. The strip 20 is provided with an integral stationary contact 23, while the strip 21 has rigidly secured thereto the spring-strip 25, which normally raises the armature 10, an insulating-block 26 being interposed, and has a transversely-extending arm 27, adapted to 95 coöperate with the stationary contact 23 to close an electric circuit therethrough, the said portion 27 of the spring 25 being given a downward bend, so as to close the circuit between these two contacts in the initial movement of the armature.

At the front end of the armature an arm 30 (best seen in Fig. 6) is secured in any desired manner thereto and projects forward over the plates 2 and 5, which are suitably notched at 2^a to allow the said arm to vibrate 105

therein and has a downwardly - extending portion 31 between the plates 2 and 3 and close to the plate 2, provided with a foot or lug 32, which bears upon a rivet or spindle 33, mounted in the arms 34 of the segmental or arc-shaped target 35. This target comprises a segmental surface plate 35^a, the side pieces 34^a, and the arms or levers 34, all being stamped and pressed from a single piece of metal and may therefore be of as light material as desired. It is pivoted upon a pin 36, extending through apertures 37 in its arms 34 and the journals or supports 38, secured to the inside of the front plate 3. The rivet, and of course the foot 32 of the arm 30, carried by the armature, may be of hard metal, which wears much better than where the arm bears directly upon a flap or shutter, as in some constructions, since such flap or shutter is usually of soft light material. Again, this arrangement admits of a comparatively long leverage in operating the target and at the same time obtains sufficient movement thereof, all of which results in an easily-operated and satisfactory annunciator.

The lower part of the segmental face of the target is provided with a number or indication corresponding to that of the annunciator. When installed, the target projects through suitable apertures in the plate 3 and beyond the front face, and to prevent mechanical injury thereto and cause the indication to be more distinctive it is covered by the semicylindrical arc-shaped or segmental sheet-metal covering 40, as shown in Figs. 1 and 2, and which is provided with an opening or window 41, through which the numeral on the target is adapted to be displayed when the armature and target are operated. The outer surface of the segmental covering 40 is preferably colored black, in which case the upper part of the segmental target would be also colored black, so that under normal conditions the opening in the covering 40 would not attract attention. It will be seen that this covering is practically in the nature of a convex cap secured to the forward end of the annunciator structure. In a single annunciator this covering is inclosed by the end pieces 42, formed integrally therewith and having the outwardly - turned flanges 43, through which screws may be passed to secure the same to the front plate 3. The device, however, may handily be arranged to accommodate a strip of several side by side by merely extending the plates 2 and 3 and the segmental covering-strip 40, such construction being indicated in dotted lines in Figs. 1, 3, and 5.

From the above matter it will be obvious that a simple, cheap, efficient, and durable annunciator is produced, one that is easily inspected or repaired, and one that is convenient to install or replace.

Various changes, alterations, and modifi-

cations may be made therein and not depart from the spirit or scope thereof.

The invention is defined in the following claims:

1. An annunciator comprising an electromagnet, a frame secured to the forward end of said magnet, a target pivoted upon said frame, a convex cover secured to the forward end of the frame in front of the target, said cover being provided with an opening adapted to expose the face of the target, the curvature of the cover corresponding to the arc described by the forward end or face of the target, and an armature arranged to raise the forward end of the target. 70

2. An annunciator comprising an electromagnet, a convex cap secured to the forward end of the magnet structure and provided with an opening, the pivoted target having a convex face adapted to swing in close proximity to the curved inner surface of said cap, and an armature for actuating said target. 85

3. In an annunciator, a supporting - plate having an aperture therein, a target having an arc-shaped face and a rearwardly-extending arm or arms projecting through said aperture, and pivoted on said support, an arc-shaped covering for said target having an aperture or window through which the target may be displayed, a magnet and armature in the rear of said supporting-plate, connections between the said armature and extended target-arms to operate the target. 90

4. In an annunciator, a supporting - plate having an aperture therein, an arc-shaped target having rearwardly - extending arms projecting through said aperture, and pivoted on said plate, a covering over the same similar in form to the target and having an opening therefor, a rivet or pin between the ends of the target-arms, a magnet in the rear of said supporting-plate, an armature therefor, an arm carried by said armature and adapted to act upon the rivet or pin and the target-arms to operate the same. 100

5. In an annunciator, two supporting-plates spaced apart, the front plate having an aperture therein, a target having a segmental face and rearwardly - extending arms, said arms being pivoted to said apertured plate at the center of the curve of the face and extending beyond the pivot and having a pin therethrough, a magnet secured to the rear face of the other supporting-plate, a longitudinal armature therefor, an arm affixed to said armature and extending down between the said plates, said arm having a foot portion adapted to bear upon said pin to operate the target upon the operation of the magnet and armature. 115

6. The combination of a convex cap provided with an opening, a pivoted target arranged back of said cap, the indicating end of said target being normally depressed, an electromagnet arranged back of said target, 120

and an armature extending lengthwise above the magnet and provided with an arm adapted to engage the rear end of said target, the armature when attracted operating to raise 5 the forward end of the target.

7. The combination of an electromagnet, two plates separated by four short members and rigidly connected with the forward end of the magnet, a convex cap secured to the 10 outer of said plates and provided with an opening, a pivoted target arranged back of said cap, and an armature having a forwardly-extending arm adapted to engage said target.

15 8. An annunciator, comprising a magnetic core having a relatively flat pole-piece disposed in the plane of one end and having its other end extended, an armature provided with a rear vertical portion suitably mounted 20 on the extended rear end of the core and having its horizontal portion overlying the pole-piece, a finger on the forward end of the armature, a spring tending normally to keep the armature raised, and a target hung on the 25 forward end of the magnet structure and held in a normally lowered position, said target having a rearwardly-extending projection underlying the said finger, whereby said target is raised when the armature is attracted.

30 9. An annunciator comprising a magnetic core having a relatively flat pole-piece disposed in the plane of one end, an armature provided with a rear vertical portion suitably mounted at the other end of the magnet and 35 having its horizontal portion overlying the pole-piece, the forward end of said armature being provided with a finger, a target hung from the forward end of the magnet structure, and a spring-switch tending normally to 40 keep the armature raised, said target being normally down and having a rear projection underlying the said finger, whereby the target is raised when the armature is attracted.

10. An annunciator, comprising an electro-45 magnet, pieces of insulation secured to the opposite ends of said magnet, pole-pieces also secured to the opposite ends of said magnet, an armature mounted upon the rear end of the magnet structure and having its horizon- 50 tal portion overlying both pole-pieces, par-

allel terminal strips rigidly secured to said pieces of insulation at opposite sides of the magnet, a shutter carried by the forward end of the magnet structure and operated by said armature, and switch-contacts carried by said 55 terminal strips beneath the armature and operated by the latter.

11. An annunciator comprising an electromagnet, pieces of insulation secured to opposite ends of said magnet, an armature suitably mounted upon the rear end of the magnet structure and having its horizontal portion overlying the magnet, a shutter engaged and operated by the forward end of the armature, terminal strips secured to said pieces 60 of insulation at opposite sides of the magnet, and switch-contacts carried by the said terminal strips beneath the armature and opened and closed by the latter.

12. In a signaling device, the combination 70 with a magnet having a coil, insulating-supports at each end of the coil, a core therefor, end pieces affixed to said core, an armature extending longitudinally of the coil and co-operating with the end pieces, electrical contacts carried by said insulating-supports, one of said contacts being of spring material to return the armature to normal position, means to close the said contacts in the initial movement of the armature, and the signal-indicating 75 device operated by said armature in its forward movements.

13. In an annunciator, the combination with a magnet of a core and end pieces therefor, insulating-blocks between the end pieces 85 and the coil, longitudinal strips secured to said insulating-pieces, stationary contact on one strip, a spring-contact on the other strip and adapted to co-operate with the stationary contact, an armature extending longitudinally of the coil pivoted at one end and adapted to be retracted by said spring-contact, and a signaling device operated by said armature.

Signed by me at Chicago, Cook county, Illinois, this 27th day of March, 1901.

HALVOR M. OLSEN.
